CLAIM

The ornamental design for a closure-penetrating support for a bottle, as shown and described.

DESCRIPTION

FIG. 1 is a top perspective view of a closure-penetrating support for a bottle, showing my new design;

FIG. 2 is a top plan view thereof;

FIG. 3 is a left side elevational view thereof, the right side being a mirror image thereof; and

FIG. 4 is a bottom plan view thereof.

FIG. 1.

FIG. 2

FIG. 3

FIG. 4
